UNITED STATES PATENT OFFICE.

HERMANN WEDER, SR., AND CHARLES H. WOLFF, OF PHILADELPHIA, PENNSYLVANIA.

TOILET-BRACKET.

1,108,043.

Specification of Letters Patent. Patented Aug. 18, 1914.

Application filed March 21, 1913. Serial No. 756,003.

To all whom it may concern:

Be it known that we, HERMANN WEDER, Sr., and CHARLES H. WOLFF, citizens of the United States, residing at Philadelphia, in the county of Philadelphia and State of Pennsylvania, have invented certain new and useful Improvements in Toilet-Brackets; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to brackets for holding toilet and other articles; and it has for its object to provide such a bracket having features of construction hereinafter specified and formed from one piece of sheet metal cut and stamped or bent into shape in a manner to impart strength to the several features and to the bracket as an entirety and to facilitate and lessen the cost of production.

In the accompanying drawing illustrating the invention Figure 1 is a front elevation of the complete article; Fig. 2 a vertical central section; Fig. 3 a plan view of the pattern, showing portions cut preparatory to being bent into shape, with the soap holder portion depressed and the portion at the other end cut to form the tumbler holder and support for brushes; and Fig. 4 is a top plan view of the bracket.

In the drawing the numeral 1 designates the pattern from which the bracket is formed and consists of a plate of sheet metal which is formed at one extremity with a dish-shaped depression 2 adapted when bent at right angles to the body portion 3 to form a soap receptacle or holder 4 and which is formed with transverse raised beads 5 which will raise a cake of soap above the drippings that may settle in the bottom of the dish. The body portion 3 is slotted centrally, in a longitudinal direction as shown at 6, so as to form a prong 7 which is bent downwardly and then upwardly beneath the portion 4 to form a hook designed to serve as a towel support which being beneath the soap dish will protect the towel from water that may drip from the soap when replacing the soap in the dish. The body portion is furthermore slotted toward opposite

edges as shown at 8 so as to form portions that may be bent outwardly and upwardly to form prongs 9 which will form a support for a comb that may lie within the crotch of the two prongs. The body is furthermore slotted as indicated at 10 and the enclosed portion bent outwardly to form a prong 11 relatively longer than the other prongs to form a clasp for a tube or bottle of tooth paste or other toilet article; and at the opposite side thereof the body portion is slotted as at 13 and bent to form a prong 14 which will serve to clasp a hair brush. The end of the pattern opposite to the soap dish is bent forwardly at right angles to the body portion to form an overhanging shelf 15 which may be formed with a central opening 16 to receive a tumbler or a sponge, and has a number of recesses 17 cut in its peripheral edge to constitute supports for tooth brushes, nail brushes, or other articles. The shelf portion is also slotted as at 18 and 19, near opposite sides, so that the contained portions may be bent downwardly and outwardly beyond the sides of the body portion to form hooks 20 and 21 designed to support wash-rags or other like toilet articles.

In order to brace and give strength to the overhanging shelf, the shelf portion is slotted at the points 22 and 23 and the portions bent to form lips 24 and 25, and the body portion near the angle bend of the shelf is slotted as at 26 and 27 so as to form prongs 28 and 29 that may lap over the lips 24 and 25 and bear against the underside of the shelf so as to stiffen and brace the shelf at its union or connection to the body portion of the bracket.

The entire article is made from a single piece of sheet metal stamped and bent into shape, the bent portions serving to brace and stiffen the associated features, and serving by a reason of the relative position of the several parts to make the bracket a most serviceable and convenient article particularly adapted for bath-room although capable of other uses.

Having described our invention and set forth its merits what we claim is:

1. The toilet-bracket comprising a sheet-metal member having a portion at one end formed with a depression and bent at right angles to the body portion to form a soap-dish with a portion of the body above the

dish cut and bent into hook-form beneath the dish, and the opposite end of the member bent at right angles to the body portion to form a shelf, and a part of the body next to the shelf being slit and bent to form prongs engaging the lips of the shelf to brace the bracket at the angle union of the shelf and body portion, substantially as described.

10 2. The toilet-bracket comprising a sheet-metal member having one end bent at right angles to the body portion to form a shelf.

said shelf having a central opening and its peripheral edge notched and portions of the shelf slit and bent to form depending ¹⁵ hooks beneath the shelf, substantially as described.

In testimony whereof we affix our signatures in presence of two witnesses.

HERMANN WEDER, Sr.
CHARLES H. WOLFF.
